DESIGN FOR A BUTTER MOLD OR SIMILAR ARTICLE

John L. Wade, Los Angeles, Calif., assignor to
Pacific Industries, Inc., Los Angeles, Calif., a
corporation of California

Application September 25, 1941, Serial No. 103,512

Term of patent 14 years

To all whom it may concern:

Be it known that I, John L. Wade, a citizen of the United States, residing at Los Angeles, in the county of Los Angeles and State of California, have invented a new, original, and ornamental Design for a Butter Mold or Similar Article, of which the following is a specification, reference being had to the accompanying drawing, forming part thereof.

Fig. 1 is a top perspective view;
Fig. 2 is a bottom perspective view;
Fig. 3 is a side elevational view; and
Fig. 4 is an end view of a butter mold showing my new design.

I claim:

The ornamental design for a butter mold or similar article, as shown.

JOHN L. WADE.
